TOWEL HOOK

Jean M. Snyder, Bronx, N.Y., assignor to Glovemakers, Inc., Chicago, Ill., a corporation of Illinois

Filed Oct. 24, 1963, Ser. No. 77,146

Term of patent 3½ years

(Cl. D4—3)

I claim:

The ornamental design for a towel hook, substantially as shown.
